UNITED STATES PATENT OFFICE.

STANLEY G. MAYERS, OF CHICAGO, ILLINOIS, ASSIGNOR OF SEVEN-TWENTIETHS TO CHARLIE KAREL AND HELEN KAREL, BOTH OF CHICAGO, ILLINOIS.

RAIL JOINT.

Application filed July 15, 1926. Serial No. 122,568.

The present invention relates to rail joints and has for its main object the provision of a rail joint which is of simple and inexpensive construction and which possesses great 5 durability and which is capable of ready assembling.

Another object of the invention is the provision of a rail joint which does not require any bolts and nuts usually employed 10 in holding the several parts together.

Another object of the invention is the provision of a rail joint of the type stated with locking means to hold the several parts of the device in assembled position.

With the above general objects in view and others that will appear as the nature of the invention is better understood, the same consists in the novel construction, combination and arrangement of parts herein- 15 after more fully described, illustrated in the accompanying drawing and pointed out in the appended claims.

In the drawing forming a part of this application, and in which like designated 20 characters refer to corresponding parts throughout the several views,

Fig. 1 is a top view of the chair and base with the rails removed;

Fig. 2 is a top plan view of the device 25 with the rails in joined position;

Fig. 3 is a cross-sectional view on line 3-3 of Fig. 2;

Fig. 4 is a cross-sectional view on line 4-4 of Fig. 2; and

Fig. 5 is the side view of the rail showing the construction thereof which cooperates with the remaining parts of the invention.

The invention comprises chair 10 provided 30 with horizontal flanges 11 laterally disposed of said chair, which are provided with a series of holes 12 permitting mounting of the chair to the ties by means of spikes or the like. Integrally formed with and upwardly projecting from said chair on one side of the rail is a fishplate 13, which on the rail side is suitably formed to entirely fill the space between the head 14 and base 15 of the rail, as clearly seen on Figs. 3 45 and 4.

Integrally formed or mounted within said fishplate is a tongue 16 which overhangs by its projecting end the chair 10. On the line horizontally with said tongue is a series 55 of lugs 17 likewise mounted in or integrally

formed with said fishplate 13. The ends of two adjacent rails in the web portions thereof are provided with apertures 18 wherein in the operative position of the rails lugs 17 are received. The rails at their terminations 60 and in the web portions thereof are further provided with slots 19 for receiving therewithin the tongue 16 when the rails are in joined position as shown on Fig. 4. It is observed that slots 19 are of a length substantially one-half of the width of tongue 16 so that the resulting slot of the two cooperating rails when they are in joined position 65 may be entirely filled by said tongue 16. The outer ends of lugs 17 remain flush with 70 the adjacent face of the web of the rail as seen on Figs. 2 and 3, while the outer end of tongue 16 extends beyond said face of the web and remains directly above the edge of base 15 as plainly seen on Fig. 4. Said 75 end of tongue 16 is provided with head 20 for the purposes hereinafter mentioned.

When the two rails have been positioned upon chair 10 and are in cooperative engagement with tongue 16 and lugs 17, wedge 21 is passed longitudinally of the joined ends 80 of two rails for the purpose of holding said rails in their joined position. Rigidly formed with and upwardly extending from said chair 10 on the other side thereof is 85 plate 22 which prevents the lateral shifting of wedge 21 when the same remains in operative position illustrated on Figs. 2, 3 and 4. It will be seen that in the last mentioned 90 operative position said wedge 21 will remain interposed between the plate 22 and the adjacent face of the web of the rails.

Wedge 21 has a cutaway portion 23 permitting the insertion of the wedge. To strengthen the structure and to prevent the 95 creeping movement of the several parts which may be caused by the vibration the wedge is further provided with a longitudinal groove 24 wherein head 20 of the tongue 16 is accommodated, as clearly seen on Fig. 4. 100

It is observed that said cutaway portion 23 and groove 24 do not extend throughout the entire length of the wedge, but only through a portion of the wedge which is sufficient to insert the wedge into its operative 105 position as is apparent from Fig. 2.

Near one of its ends chair 10 is provided with an opening 25 and an aperture 26 which leads from said opening. The solid 110 end of the wedge 21 is provided with a

similar opening 27 for receiving plug 28. Before the wedge 21 is inserted into its operative position hereinabove described the plug 28 is inserted within opening 27 and then the wedge is driven into its operative position. As soon as openings 25 and 27 register with each other plug 28 will fall within said opening 25 and the lower portion of said plug 28 will entirely fill said opening, while the upper portion of said plug 28 will remain within the opening 27 in the wedge. Thus it will be seen the plug 28 will provide a locking means between the wedge 21 and chair 10 preventing the withdrawal or any creeping movement of wedge 21 from its operative position. When it becomes necessary for any reason to withdraw wedge 21 in order to disassemble the several parts of the rail joint, opening 26 serves as an access for any instrument such as nail or the like to raise plug 28 within opening 27 and when that is accomplished the wedge may be moved in the opposite direction for the purpose of withdrawing the same from its operative position.

While there is described herein a preferred embodiment of the present invention, it is nevertheless to be understood that minor changes may be made therein without departing from the spirit and scope of the invention as claimed.

What I claim as new is:

1. The combination with the rails, of a chair, a fishplate integrally formed with said chair and upwardly projecting therefrom, a tongue laterally projecting from said fishplate, said rails having at their web portion a slot for permitting passage of said tongue, lugs laterally projecting from said fishplate, said rails having openings for accommodating said lugs, another plate integrally formed with and projecting from said chair, and a wedge positioned between said last named plate and the web portion of the rails, said tongue having a head at its end engaging said wedge for preventing the lateral creeping movement thereof.

2. The combination with the rails, of a chair, a fishplate integrally formed with said chair and upwardly projecting therefrom, a tongue laterally projecting from said fishplate, said rails having at their web portion a slot for permitting passage of said tongue, lugs laterally projecting from said fishplate, said rails having openings for accommodating said lugs, another plate integrally formed with and projecting from said chair, and a locking means between said chair and said wedge for preventing longitudinal sliding movement of

the wedge when the same remains in operative position.

3. The combination with the rails, of a chair, a fishplate integrally formed with said chair and upwardly projecting therefrom, a tongue laterally projecting from said fishplate, said rails having at their web portion a slot for permitting passage of said tongue, lugs laterally projecting from said fishplate, said rails having openings for accommodating said lugs, another plate integrally formed with and projecting from said chair, and a locking means between said chair and said wedge for preventing longitudinal sliding movement of the wedge when the same remains in operative position, said means including registering holes in said chair and said wedge and a plug within said holes.

4. A rail joint comprising a chair, a fishplate integrally formed with and extending upwardly therefrom, a tongue laterally extending from said fishplate, the two joined rails having at their web portions a slot for permitting passage of said tongue, lugs laterally projecting from said fishplate, said joined rails having openings in their web portions for accommodating said lugs, another plate upwardly extending from said chair, a wedge between said last named plate and the rails for preventing lateral shifting of the rails, said chair and the wedge having registering openings, and a plug sitting within said openings for preventing longitudinal shifting of said wedge.

5. A rail joint comprising a chair, a fishplate integrally formed with and extending upwardly therefrom, a tongue laterally extending from said fishplate, the two joined rails having at their web portions a slot for permitting passage of said tongue, lugs laterally projecting from said fishplate, said joined rails having openings in their web portions for accommodating said lugs, another plate upwardly extending from said chair, a wedge between said last named plate and the rails for preventing lateral shifting of the rails, said chair and the wedge having registering openings, and a plug sitting within said openings for preventing longitudinal shifting of said wedge, said chair being further provided with an aperture communicating with the said opening in the chair for shifting the plug into the said opening in the wedge allowing the removal thereof from its operative position.

In testimony whereof I affix my signature.

STANLEY G. MAYERS.
